William W. Stevens, of Westbrook, Maine.
Assignee to Nath. P. Richardson, & Co. of Portland,
Letters Patent No. 1127. Dated July 26, 1859.

The schedule referred to in these Letters Patent, and making part of the same.

To all whom it may concern;

Be it known that I, William W. Stevens, of the Town of Westbrook, County of Cumberland and State of Maine, have invented or produced a new and original design for the Iron Castings for an Urn, Top, Base, Door frame, Bottom and legs to be used with sheet iron body in making a "Coal Parlor" or Coal Parlor Cooking Stove and I do hereby declare, that the following is a full and exact description of the same, reference being had to the annexed photographic representations of the same.

Of said Photographs.

F.P.

I claim the configurations, ornaments and moldings as a design for an Urn, Top, Door and frame, Base, Bottom and Legs to be used with a sheet iron body in making a coal parlor or coal parlor cooking stove as above described and represented in the accompanying drawings.

In testimony whereof I have hereunto set my hand and seal this seventh day of July 1859.

Witnesses.

John H. Hall.

W. A. Parsons.
